DRINKING FOUNTAIN

Filed Aug. 25, 1927

Inventor:

THOMAS S. CATLIN,

834 Edgar M. Kitchin,
His Attorney

UNITED STATES PATENT OFFICE

THOMAS S. CATLIN, OF WAVELAND, INDIANA, ASSIGNOR TO STERLING MANUFACTURING COMPANY, OF FORT WAYNE, INDIANA, A CORPORATION OF DELAWARE

DRINKING FOUNTAIN

Application filed August 25, 1927. Serial No. 215,320.

This invention relates to improvements in apparatus for insuring sanitation in the matter of delivery of drinking water or other liquid to be directly quaffed.

5 The primary objects in view are accentuation of sanitation and facility of use in connection with an ordinary spigot.

More detailed objects will become apparent hereinafter and will in part be stated.

10 With these and other objects in view, the invention includes a baffle disposed in the path of discharge from a font and a control actuated thereby for governing drainage from the discharge.

15 The invention in greater detail includes a baffle located in the path of discharge of a drinking font and a control valve for the drainage of the font connected to the baffle for enabling the baffle to close the valve against 20 drainage during the regular flow from the font.

The invention also comprises certain other novel constructions, combinations, and arrangements of parts as subsequently specified 25 and claimed.

In the accompanying drawings,—

Figure 1 is a longitudinal, vertical, central section of an apparatus embodying the features of the present invention and shown as 30 applied to a spigot, the latter being seen in elevation.

Figure 2 is a horizontal section taken on the plane indicated by line 2—2 of Figure 1, looking downward.

35 Figure 3 is a vertical section taken on the plane indicated by line 3—3 of Figure 1, and looking in the direction indicated by the arrow.

Figure 4 is a view similar to Figure 1 of a 40 somewhat modified embodiment, parts being broken away for the saving of space.

Referring to the drawings by numerals, 1 indicates the ordinary house spigot having the usual discharge nozzle 2. A clamp 3 detachably engages the nozzle 2 in position for leaving the lower or extreme edge portion of the nozzle exposed beneath the clamp. The clamp 3 is susceptible of quite a wide range of modification in the details of its construction, but preferably includes a pair of arms

4 from which outstands rearwardly a plate 5. The arms 4 are internally, transversely grooved and contain a gasket 6 which snugly surrounds the nozzle 2. The gasket 6 is an appropriate packing unit, and may be a ground metal ring or a soft metal packing or of other appropriate packing material, such as rubber or leather, and is preferably cross-cut at 6' to facilitate assemblage within the arms 4. The gasket is assembled in the arms before the clamp 3 is applied to the nozzle 2. The outer or forward ends of the arms 4 are formed into outstanding parallel tabs 7, 7, perforated and engaged by a bolt 8 passing through said tabs and designed to draw the free end portions of the arms 4 toward each other for firmly clamping the gasket 6 against the circular exterior surface of nozzle 2. Of course, the arms 4 are permitted to spring apart by relaxing or backing-off the nut of bolt 8 when the clamp 3 is to be applied or removed from the nozzle 2.

A fountain tube 9 is arranged with a rearward extension 10 disposed with its upper face parallel and contiguous to the under face of the plate 5. A bolt 11, or other appropriate anchorage, depends from the plate 5 and sustains the extension 10 and its connected parts. Bolt 11 preferably is headed, and has its head seated in an appropriate recess in the upper face of plate 5, and depends through the plate and through the extension 10 and is engaged by a clamp nut 12 between which nut and the extension 10 a coiled spring 13 is interposed, so that screwing up on the nut 12 will compress the spring 13 against the extension 10, and thereby stress the extension 10 toward the plate 5 and elastically support the extension 10 and its connected parts. As a matter of finish in appearance, the extension 10 is preferably recessed at 14 to accommodate the spring 13, and the recess is sufficiently large to admit the nut 12 so that the spring is concealed.

The tube 9 is thus retained under tension 95 stressing it upward toward the discharge end of the nozzle 2, and the tube 9 is provided with a gasket 15 surrounding the inner terminus of the bore of the tube and located to contact with the exposed edge of the nozzle 100

2 under sufficient stress of the tension of spring 13 to effect a non-leaking joint between the nozzle 2 and the bore of the tube 9. Upstanding from the extension 10 preferably at diametrically opposite sides of the bolt 11 are lugs 16, 16, disposed to engage cam faces 17, 17 in the under portion of plate 5, said cam faces being proportioned and located to cause the extension 10 to move downward against the tension of spring 13 whenever the tube 9 is swung horizontally about the bolt 11 as a pivot. The cam faces 17 are preferably formed in recesses in the plate 5 so as to be concealed, and are so located that when the tube 9 is positioned to outstand directly from the spigot 1 the lugs 16 will be in engagement with the highest points of the cams 17, so that the gasket 15 will be in intimate contact with the nozzle 2. Thus, during operation, the joint between the spigot and the tube 9 remains sealed, but, when the operator desires to use the spigot independently of the tube 9, it is only necessary for him to swing the tube 9 laterally, which action is accompanied by a movement of the extension 10 downward incident to the engagement of the lugs 16 and movement thereof along the cams 17. This downward movement insures an effective clearance of the gasket 15 from the formerly engaged edge of the nozzle 2. Return movement of the tube 9 causes the parts to snap into the seated position formerly occupied, and, as shown in Figure 1 of the drawings.

The tube 9 is susceptible of a substantial range of variation in the details of its construction and includes preferably a horizontal section and an upstanding section, the latter carrying a discharge nozzle 18. The nozzle 18 is laterally enlarged beyond the bore of the tube 9 and provided with jet openings 19, 19, located to project a fountain or jet of water, or other liquid to be consumed upward under the hydraulic head of the source of supply through the spigot 1. A baffle plate or concavo-convexed disc 20 formed with drain apertures 19' is arranged within the enlarged portion of the nozzle 18, and is fixed to a stem or rod 21 which depends through the upstanding portion of the tube 9 and extends through the lower wall of the tube, the lower end portion of the stem 21 carrying a valve 22 designed to be seated on the valve surface 23 formed in said lower wall. Thus, when the water is turned on through the spigot 1, it flows as indicated by the arrows in Figure 1, the upstress of the stream flowing upward through the upstanding portion of tube 9 striking the baffle or disc 20 and elevating the same until the valve 22 is thereby firmly seated and seals the opening in the lower wall of tube 9 against leakage. This condition continues as long as the water flows from the spigot 1

and out through the apertures 19. As soon as the operator turns off the spigot 1, the cessation in the up stress of the water allows the disc 20 to drop and thereby open the valve 22, so that the water within the tube 9 is allowed to flow freely from the tube and completely drain the same. Hence, any particles of saliva, bacteria, or other objectionable matter that might have otherwise been retained in the fountain is drained out each time the spigot is turned off.

In Figure 4 is illustrated a structure similar to that above described, and sufficiently corresponds thereto to bear the same reference numerals and have the same description apply, except that the valve seat 23' formed in the tube 9 is preferably located at a point in line with the discharge from the nozzle 2 of the spigot instead of at the outer extremity of the horizontal portion of the tube. The advantage of this change in location will become apparent immediately. The tube 9 of the structure seen in Figure 4 is provided with a depending enlargement 9' about the place where the valve seat 23' is provided, and a cross plate or bracket 24 is arranged within the enlargement 9' and through which bracket extends the stem 21' of the valve 22'. The stem 21' upstands beyond the bracket 24 and is provided with a disc 20' in the line of discharge and immediately beneath the lower end of the nozzle 2. A preferably relatively light spring 25 surrounds the stem 21' between the disc 20' and the bracket 24, and is tensioned to sustain the disc 20', stem 21', and valve 22' under ordinary non-operating conditions, so that the port formed by the valve seat 23' is retained open when the parts are not in operation. In operating the structure seen in Figure 4, as soon as the water is turned on, the pressure of discharge on top of the disc 20' overcomes the tension of spring 25 and seats the valve 22' so that the tube 9 is thereby sealed, and the discharge through the font nozzle continues the same as described with reference to the structure seen in Figure 1. However, when the supply of liquid is cut off, as by the closing of the spigot, cessation of pressure on top of disc 20' permits the spring 25 to function and lift the valve 22' from its seat. Thereupon, the liquid within the tube 9 drains out of the tube in substantially the same manner as occurs in the operation of the structure seen in Figure 1.

It is particularly to be noted that every facility is provided for insuring a sanitary condition by the effective and complete drainage of liquid remaining in the fountain 2 at the time the pressure is cut off. The apertures 19 and 19' assure a complete back drainage of every particle of moisture, so that the liquid can escape freely past the valve seat 23.

Novel subject matter disclosed but not herein claimed is the subject of claim in my

co-pending application Serial No. 313,863, filed October 20, 1928.

What is claimed is:

1. In a drinking fountain, the combination, with a discharge tube having a draining opening, of means alined with the discharge of said discharge tube and adapted to be actuated by the pressure of liquid being discharged for closing said draining opening. 5
  2. A drinking fountain comprising a tube having a font nozzle and a drain opening, of a valve for closing said opening, and a baffle in the path of discharge through the font, and means connecting the baffle with the valve for seating said valve. 10
  3. A drinking fountain comprising a tube having a font nozzle and a drain opening, of a valve for closing said opening, and a baffle in the path of discharge through the font, and means connecting the baffle with the valve for seating said valve, the valve being provided with means for unseating the same upon discontinuation of the font discharge. 15
  4. A drinking fountain comprising a tube having a font nozzle and a drain opening, the font nozzle being enlarged laterally relative to the bore of the tube, a baffle within said nozzle of an area equal to the transverse area of said bore, and means actuated by said baffle for closing and opening said drain opening. 20
  5. A drinking fountain comprising a tube having a font nozzle, the tube having a discharge end within the nozzle, a baffle plate within the nozzle overhanging said discharge end in position for being elevated by the discharge, and a drainage valve connected to be actuated by said plate. 25
  6. A drinking fountain comprising a tube having a font nozzle, the tube having a discharge end within the nozzle, a baffle plate within the nozzle overhanging said discharge end in position for being elevated by the discharge, and a drainage valve connected to be actuated by said plate, the said baffle plate being formed with a drainage opening for insuring drainage of moisture at the upper part of the plate when the discharge is cut off. 30
  7. A drinking fountain comprising a tube having a font nozzle, the tube having a discharge end within the nozzle, a baffle plate within the nozzle overhanging said discharge end in position for being elevated by the discharge, and a drainage valve connected to be actuated by said plate, the said baffle plate being formed with a drainage opening for insuring drainage of moisture at the upper part of the plate when the discharge is cut off, the upper face of said baffle plate being convexed. 35
  8. A drinking fountain comprising a tube having a font nozzle and a drain opening for draining the nozzle when the flow there- 40
  - through ceases, and means in the path of the full flow through the tube actuated by such flow to close said drain opening. 45
  9. A drinking fountain comprising a tube having a font nozzle and a drain opening for draining the nozzle when the flow therethrough ceases, the tube being shaped to cause a change in direction of flow of liquid therein and the drain opening being at the place of such change in direction, means for closing said drain opening, and means in the path of and actuated by the full flow in said tube for effecting closing action of said closing means for the drain opening. 50
  10. A drinking fountain comprising a tube having a nozzle through which the tube discharges, and a drain opening for draining the nozzle when the flow therethrough ceases, a baffle arranged directly in the path of the full flow of said tube, and means actuated by movement of the baffle incident to the action of said full flow for closing the drain opening. 55
